KEY PUNCH

James V. Simone, 502 Sherbrook Drive, High Point, N.C.

Filed Sept. 7, 1962, Ser. No. 71,597

Term of patent 14 years

(Cl. D64—11)

FIGURE 1 is a front perspective view of a key punch showing my new design;

FIGURE 2 is an end elevational view thereof looking from the right side of FIGURE 1;

FIGURE 3 is another end elevational view thereof but looking from the opposite end;

FIGURE 4 is a rear elevational view thereof;

FIGURE 5 is a front perspective view of another embodiment of the key punch shown in FIGURE 1;

FIGURE 6 is an end elevational view thereof looking from the right side of FIGURE 1;

FIGURE 7 is another end elevational view thereof but looking from the opposite end; and

FIGURE 8 is a rear elevational view thereof.

The dominant features of my design reside in those portions shown in full solid lines.

I claim:

The ornamental design for a key punch, substantially as shown and described.
